CAN OPENING AND SEALING IMPLEMENT

Arthur Mull, Ottawa, Ill.

Application January 8, 1948, Serial No. 1,149

1 Claim. (Cl. 220—51)

1

My invention relates to improvements in can opening and sealing implements for use with milk cans of the type used in the household for dispensing evaporated milk and the like.

The primary object of my invention is to provide a simple form of device of inexpensive construction especially adapted for punching a pair of pouring and air vent holes in the top of such cans, and which is equipped for snap action attachment to the tops of said cans to seal the holes when not in use.

Other and subordinate objects, within the purview of my invention, together with the precise nature of my improvements will be readily understood when the succeeding description and claim are read with reference to the drawing accompanying and forming part of this specification.

In said drawings:

Figure 1 is a view in plan of my improved can opener and sealing device in a preferred embodiment thereof attached to a can in sealing position;

Figure 2 is a fragmentary view in vertical transverse section of the same;

Figure 3 is a view in bottom plan of the shank of the implement;

Figure 4 is a view in perspective of the same;

Figure 5 is a view in perspective of the claw member detached and drawn to a larger scale;

Figure 6 is a view in perspective of the head of the shank;

Figure 7 is a view in perspective of the snap fastener member.

Referring now to the drawing by numerals, the implement of my invention comprises a flat, bar shank 1 of any suitable light strong material.

A tapered punch 2 is formed on one end of the shank 1 co-planar therewith for forming holes in the top 3 of the usual milk can 4 provided by the trade for household and like use, and the punch 2 is formed with an enlarged rear end spreader portion 5 for enlarging such holes, if desired.

A button-like head 6 is provided at the other end of the shank 1 and is suitably fixed on an axial stud 7 on said shank against a shoulder 8 on the shank for use in driving the shank 1 either by hand or otherwise to force the punch 2 into the top 3 of the can 4.

The shank 1 is of a suitable length to extend diametrically across the top 3 of a can 4 of a given size with the punch 2 and head 7 spaced from opposite sides of said can, and has pressed out from the same on one side thereof and in the longitudinal center of the same a pair of conical

bosses 9 spaced apart and adjacent opposite ends of said shank for entering a pair of holes 10 formed in the top 3 of said can 4 adjacent diametrically opposite sides of said top.

5 A claw member 11 is provided for the punch end of the shank 1, between said end and one boss 9, comprising a rectangular clip 12 fitting part-way around the shank 1 and in a pair of side edge notches 13 in said shank, the clip 12 having a pair of right angled claws 14 extending at a right angle therefrom on the same side of the shank 1 as the bosses 9 and which are adapted to hook under the usual circumferential flange 15 on the top 3 of said can 4. The claw member 11 is preferably formed of spring steel for assembly and another purpose presently seen.

10 A snap fastener member 16 is provided on the head equipped end of the shank 1, between said end and the other boss 9, comprising a clip 17 partly surrounding said shank and fitting in a pair of edge notches 18 in said shank 1, like the clip 11, said clip 17 having extending from one edge thereof on the same side of the shank 1 as the claws 14, a right angled hook catch 19 adapted to snap under the flange 15 and terminating in an outwardly curved camming lip 20. The snap fastener member 16 is also formed of resilient steel for assembly, and also for snap action purposes, as will presently be seen. The snap fastener member 16 is spaced from the claw member 11 so that the two will hook under the flange 15 at diametrically opposite sides of the can 4.

15 In using the described device, the same is positioned on the top 3 diametrically thereof with the bosses 9 equidistantly spaced from the opposite sides of the can 4, and then struck, pressed or tapped so that the bosses 9 mark the top 3 for positioning a pair of holes 10 in said top. The punch 2 is then used in a manner which will be clear, to punch the holes 10 for use as pouring and/or air vents respectively. The claws 14 are then positioned under the flange 15 and the shank 1 swung down over the top 3 using the claws 14 and said flange 15 as a fulcrum, and the bosses thus entered in the holes 10. As the shank 1 is swung into flat engagement, substantially, with the top 3, the camming lip 20 engages the edge of the top 3 and flexes the catch 19 outwardly so that when said shank 1 lies substantially flat on the top 3, the catch 19 will snap under the flange 15 and thereby lock the shank 1 to the can top 3 with the bosses 9 wedged into the holes 10 to seal the same and prevent clogging of said holes, or foreign matter entering the same. To uncover the holes 10, the catch 19 is

released by flexing the lip 20 away from the can 4 by means of the finger of a hand gripping the head 6 and thus releasing the catch 19, whereupon the shank 1 may be removed for replacement when desired.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claim.

Having described my invention what is claimed as new is:

An implement for sealing a pair of pouring holes in opposite sides of a can top of the type having an edge flange, said implement comprising a bar adapted to extend across said top and be fastened substantially flat against the same, a 20 claw member on said bar adjacent one end thereof adapted to hook under said flange to fasten said bar to said top at one side of the top, a snap action fastener member on said bar adjacent the

other end thereof adapted to hook under said flange to fasten said bar to the top at the other side of the top, and a pair of conical bosses on said bar adapted to be wedged into said holes 5 to seal the same, said claw member and said snap action fastener member comprising clips and said bar having pairs of opposite side edge notches therein in which said claw member and said snap action fastener member are fitted.
